UNITED STATES PATENT OFFICE.

GEORGE W. FOSTER, OF WESTFIELD, MASSACHUSETTS.

WINDING-MACHINE.

SPECIFICATION forming part of Letters Patent No. 789,601, dated May 9, 1905.

Application filed August 6, 1903. Serial No. 168,477.

To all whom it may concern:

Be it known that I, GEORGE W. FOSTER, a citizen of the United States, residing at Westfield, in the county of Hampden and State of Massachusetts, have invented certain new and useful Improvements in Winding-Machines, of which the following is a specification.

My invention relates to winding-machines, and more especially to that class of winding-machines in which the cop is rotated by contact with a driving drum or roll; and my invention consists in certain details of construction whereby to secure the better lay of the thread with a more uniform and stable winding and to facilitate and cheapen the manufacture and insure a greater rapidity of action, as fully set forth hereinafter and as illustrated in the accompanying drawings, in which—

Figure 1 is an end elevation, in part section, of sufficient of a winding-machine to show my improvements; Fig. 2, a longitudinal section of part of the machine. Fig. 3 is an enlarged side view of some of the parts seen when looking from the center of the machine toward the right, Fig. 1. Fig. 4 is an enlarged side view of some of the parts seen when looking from the right, Fig. 1. Fig. 5 is an inverted plan of one of the tension devices; Fig. 6, an enlarged side view illustrating part of the thread-guide-actuating mechanism indicated on a smaller scale in Fig. 2; Fig. 7, a section on the line 6 6, Fig. 6; Fig. 8, a side view showing my improved form of cop-holder device; Fig. 9 a plan of Fig. 8, and Fig. 10 is a side view showing the part K and connections.

The frame A is of suitable construction to support the operating parts of the machine, including bearings for the main shaft B, support-spindles C, and series of hollow driving shafts or sleeves D, upon each of which turns freely a belt-pulley 2, recessed at one end to constitute one member of a clutch, the other member, 3, of which slides on but turns with the shaft D. As shown, the shafts of the two series are oppositely arranged, two shafts axially in line across the frame, and a continuous belt E passes over the pulley 2 of one

shaft, down and beneath two pulleys 4 5 on the main shaft B, and up and over the pulley 50 2 of the opposite shaft.

The pulley 4 is fixed and the pulley 5 loose, and the belt E is thus driven to drive each of the oppositely-arranged shafts, the pulley 5 being an idler. Each shaft D is hollow and 55 carries a drum or roll F, and above each roll is an inclined spindle 6, supporting a cop-tube holder 7 and turning in a support shown as a box 8, from one side of which extends a trunnion 113, that turns in a socket of an arm 60 9, pivoted at 10 to a lug 12 on the frame. Collars 100 on the spindle, Fig. 1, hold it in place. The holder, on which a conical cop-tube is applied, can thus be rotated by contact with the roll, rise as the cop is wound, and will always 65 maintain one side of the cop in contact with the roll.

As the holder is secured to the spindle and the latter turns in the box, the lubricant is applied to the part in the box, so that the 70 liability of oil being deposited on the cop, which is incurred when the holder turns on the spindle, is avoided.

The tension device G may be of any suitable construction. As shown it is supported 75 by a hanger 13, recessed to receive and support a cross-bar 15, from which extend two rods 16 16 and through which passes loosely a rod 14. On the rod 14 and on two rods 16 16, extending from the bar 15, are supported 80 two bars 17 18, the former immovable and the latter capable of sliding on the rods and pressed outward by a spring 19 against a nut 23 on the threaded end of the rod 14, by turning which nut the bar 18 is shifted. A jam-nut serves to hold the nut 23 after adjustment. The bars 17 18 carry alternately-arranged L-shaped fingers 20 21, the short sections extending at right angles to the inner faces of the bars 17 18 and the long sections extending outward and bent alternately in opposite directions at the ends, and by pressing inward the bar 18 the fingers 21 connected therewith are carried inward away from the stationary fingers 20, and the yarn may be 95 passed vertically between the two series of

5 fingers, after which, on releasing the bar 18, it is carried outward by the spring, carrying its fingers between the fixed fingers and bending the yarn in a tortuous course, that secures 10 a tension thereon, increased in proportion as one series of fingers is carried beyond the other, determined by the position of the nut 23. It will be evident, however, that the bar 18 can move inward against the stress of the 15 spring in case of any excessive draft on the yarn. Each tension device is arranged above one of the supply-spindles, and a curved guide-plate 24 directs the yarn from the tension device toward the reciprocating notched 20 guide H.

The guide H slides in a longitudinal slot in a bracket 32 on the bed of the machine, and the yarn passes to the notch constituting the eye of the guide, over a curved plate 31, which 25 is hung between ears of the bracket 32, so that by swinging the plate upward the yarn may be lifted from the eye, permitting the guide to play without affecting the yarn. An arm 32 on one of the pivots of the plate 31 tends 30 to keep it in the position shown in Fig. 2. The general movements of the machine may thus be continued after any or all of the driving-rolls are stopped, as hereinafter described, this stopping being effected by disengaging 35 the clutch-sections. It will be seen that by thus lifting the yarn out of the guide the breakage of the yarn is prevented when the winding is stopped, while the guide continues to reciprocate. In its passage over the guide-plate 24 the yarn crosses a slot 33, through 40 which extends a drop-wire 34, the bent end of which, Fig. 1, bears on and is supported by the yarn so long as the latter is taut or unbroken. On the slackening or breaking of 45 the yarn, however, the bent end of the wire will swing downward through the slot and the upper end will shift its position and operate the stop devices.

The stop devices operate to detach the yarn 50 from the guide to shift the clutch to arrest the rotation of the single driving-drum by which the slack or broken yarn is being wound and also to actuate a detent which supports the cone-holder while loose ends are 55 being pieced and to open the tension and to force the drop-wire back to normal position. While capable of being differently constructed, the stop devices consist of a rod 35, Figs. 1 and 4, sliding in the hollow sleeve D and 60 projecting outward with an outer rounded knob or end 36 and connected, by a pin 121 extending through a slot in the sleeve D, with the member 3 of the clutch, which when the winding-roll is to be rotated engages the other member, 2, under the action of a spring 37. (See Fig. 1.)

The rod 35 is pressed and held inward by the contact of its knob 36 with a knob 38 on an arm 39, swinging across the end of said

65 rod and secured to a horizontal rod 40, being swung inward to carry the knob 38 into engagement with the knob 36 by the action of a spring 41, coiled round the rod 40 and connected to the frame and to a collar on the rod. (See Fig. 1.)

70 On a disk 42, carried by the sleeve D, are lugs 43, and a lever 44, Fig. 4, pivoted to the frame, has pivoted to its upper end a dog 45, having a lug 46, and said dog extends over the upper end of the drop-wire 34, and when the lower end of the latter drops on breaking or slackening of the yarn, the upper end lifts the dog and the lug 46 is engaged by one of the lugs 43 and the dog and upper end of the lever 44 are carried inward and the 80 lower end of the lever 44 moves outward in the direction of its arrow, Fig. 4, to operate a suitable detent. Thus it carries a tooth 47 on the lever 44 away from a tooth 48 on a disk 49 on the rod 40. As the teeth 47 48 85 are disengaged the spring 41 rocks the rod 40 and the arm 39 is carried with its knob 38 opposite to the end of the rod 35, pressing the latter back and carrying the member 3 of the clutch away from the member 2 and stopping the rotation of the drum F. As the drum is arrested the plate 31 is automatically 90 lifted to remove the yarn from the notch in the thread-guide by the vibration of an arm 50, Fig. 3, at the inner end of the rod 40, 95 which is connected by a slotted link 51 to an arm 52 on one of the pivots of the guide-plate 31. The link 51 is slotted, as it has a greater motion than is required to be imparted to the 100 plate 31. When the drum stops, the cone-holder may be lifted to enable the operator to get the loose end and piece the yarn. To hold it in its upward position, I provide the 105 detent K, Fig. 3 and Fig. 10, which, as shown, is an eccentric provided with an arm connected by a link 56 to allow a little lost motion with the upper end of the arm 50 to swing with the 110 latter and engage a rod 57, connected to the arm 9, supporting the cone-holder. The link 56 is slotted, as it has a greater motion than is 115 required to be imparted to the detent K. Said rod bears on a roller-stud 60 and is clamped between the latter and the eccentric-detent when the cone-holder is lifted and holds the latter in elevated position; but 120 when the shaft 40 is turned to carry the arm 39 away from the end of the rod 35 the eccentric is also turned and the rod 57 is released, allowing the cone to drop onto the 125 drum. It will be evident that while the detent when bearing on the rod 57 prevents downward motion the rod can be raised freely.

A rod 72, passing through a hole 102 (dotted lines, Fig. 4) in the frame, is pivoted to the inner face of the wheel 49 and has a hooked end extending over the dog 45, so as to draw down the latter to normal position when the shaft 40 rocks to effect the disengaging of the

clutches. The lever 44 is thrown inward at the lower end by the action of gravity, which may be supplemented, if required, by a spring, so that the lever naturally tends to occupy a 5 vertical position.

It will be seen that as soon as arm 39 swings to the left, Fig. 4, the dog 45 will be forced downward by the action of the rod 72, attached to the disk 49 and hooked over the dog 10 45, and by contact with the drop-wire will restore the latter to position.

The swinging of the lever 39 away from the rod 35 is effected by hand when the machine is to be started. As soon as the plate 31 drops 15 25 the yarn is carried by the operator to a position to be engaged by the upper rounded end of the thread-guide, and the yarn then passes over said end and into the guide-slot.

The rod 14 of the tension device is threaded 20 25 at the inner end, and a circular nut 62 turns thereon and bears against a collar $\varnothing$ between the nut and the bracket 13.

The stopping mechanism will open the tension device to allow the yarn to be drawn 25 30 freely to piece it. This is effected by connecting the nut 62 by a link 171 with an arm 170 on the shaft 40, so as to turn the nut and permit the rod 14 to move longitudinally and open the tension. A cam will effect the same 35 purpose as the nut.

There are material objections incident to the sudden reversing action of a cam for operating the reciprocating thread-guide, which reversal if quick enough to secure the requisite sharp bends at the ends of the helices in the cone results in extreme vibration, "pounding," and wear, to avoid which the speed and consequent production must be reduced. To secure the requisite quick reversal of the lay 40 45 of yarn in the cop without the objections incident to the use of a cam, I make use of a revolving crank-pin connected with the reciprocating guide and so operated as to accelerate the speed of rotation of the pin as the guide approaches the ends of the cop, and I have found that this enables me to increase the speed of the machine over that which would be possible with a cam.

As shown, the crank-pin 70 is carried upon 50 55 a support 80, which is a disk and which serves also as a fly-wheel, having a sleeve 100 rotating in a hollow hub 101 and driven by gears 85 86 from the main shaft B, and the crank-pin 70 is connected by a connecting-rod 74 to a pin 99 at the end of an arm 75 on a rock-shaft 76, an arm 77 carried with which is connected by a link 78 to the carrier of the thread-guide. The arms 75 77 are approximately in line and nearly horizontal when the 60 65 crank-pin 70 is in its upper position. These parts, as shown, are so arranged that the guide will be at the limits of its movements when the arm 75 is nearly horizontal or nearly vertical and the pin 70 is either at the top or

bottom position. If the pin 70 were secured 65 fixedly to the support 80, the carrier would approach each limit of its movement with a gradually retarded speed and the yarn instead of being reversed abruptly would be laid with a wide sweep or curve and result in impairing the form of the cop and in a loose package at the ends. I therefore combine with the pin means for causing it to travel round the axis of the support with a changing radius and increasing its speed of move- 70 75 80 85 90 95 100 105 110 115 120 125 130 135 cop and the drive-roll is along a line in the plane of their axes. As the thread mass grows and the cop swings upward the line of contact is gradually thrown out of the plane including the axis of the cop and the axis of the drive-roll. As the apex end of the spindle rises more slowly than the base end, the cop and roll will assume the position of skew-gears as the yarn mass grows and the spindle and its support swing upward. This results in reducing the contact between the roll and cop from a line the length of the cop to substantially a single point and tends to crowd the yarn on the surface and toward the large end of the cop and the stretching of the yarn causes loops, uneven winding, and uneven pressure and prevents a close and fine adjustment of the thread-guide in relation to said cop, which causes an irregular laying of the helices and also causes unevenness of pressure on the apex end of the package. To remedy this, I make use of the construction shown in Figs. 8 and 9, where the swinging arm 9 and box 8 have each a swivel connection, the box swinging in one direction on the trunnion 113, turning in the socket in the pivoted arm 9 to permit the proper slant of the cop-spindle above mentioned, and in the other direction on a pivot 101 as the winding progresses. A pivot 114 at the rear end of the box 8 secures one end of a connecting-rod 111, the other end of which swings on a stationary stud 116, eccentric to the pivot 10 of the arm 9. The result is that as the yarn mass increases in diameter and swings upward one end of the part 8 swings about the center of the pin 10 on a curve 133, while the other end of the box or bearing 8 is thrown outward and will follow a path shown by the line 123. In other words, the two extremes of the package will swing in eccentric curves, and the line of contact of the cop and roll will always be in the plane including the axis of the cop and the axis of the driving-roll. It will be seen that by changing the position of the stud 116 any desired variation can be obtained and that by employment of an extensible connecting-rod 111, as shown, the conical cop can be adjusted to a fine degree on the surface of the driving-roll.

It will be seen that by a simple adjustment of the connecting-point of the rod 78 with the lever 77 the throw of the guide may be varied. It will be evident that where the acceleration of the ends of the traverse is not required a regular cam may be substituted for the peculiar wrist-pin-operating means specified in connection with the other features of the structure.

I do not here claim, broadly, the means described of imparting the desired movement of a part operated from a crank-pin, as this is the subject of my Letters Patent for a new mechanical movement, No. 766,878, dated August 9, 1904.

Without limiting myself to the constructions and arrangements described, I claim—

1. The combination in a winding-machine, of a rotating spindle, reciprocating guide, and means for accelerating the speed of movement of the guide near the ends of its travel in each direction, substantially as set forth. 65

2. The combination with a thread-guide of a winding-machine, of a rotating support, a pin carried therewith around the axis of the support, connections between the pin and guide, and means for imparting a continuous forward but gradually-increased and then gradually-decreased speed of movement to the said pin and for moving it radially during parts of each revolution of the pin around the said axis, substantially as set forth. 70 75

3. The combination with the guide of a winding-machine, of a rotating support, a pin carried thereby, connections between said pin and the guide, means for accelerating and then retarding the movements of the pin at intervals, and means for increasing the speed of movement of the guide over that imparted by the pin, substantially as set forth. 80 85

4. The combination with the guide of a winding-machine, of a rotating support, a pin carried therewith, means for increasing and decreasing at intervals the speed of the pin in respect to its normal speed, and a rock-shaft having arms connected one to the pin and the other to the guide, substantially as set forth. 90 95

5. The combination with the guide, of a support connected therewith, a pin on said support, a rock-shaft having an arm connected with the pin, and a pivoted arm connected with the guide, and stops for vibrating the pivoted arm to increase the terminal speed of the guide, substantially as set forth. 100

6. The combination with the guide, of a rotary support, a pin, means for moving the pin at intervals independently of the support, a rock-shaft having an arm connected with the pin, and a pivoted arm connected with the guide, and stops for vibrating the pivoted arm to increase the terminal speed of the guide, substantially as set forth. 105 110

7. The combination in a winding-machine, of independent shafts arranged axially in line carrying driving-rolls and provided with pulleys, and clutches between the pulleys and shafts, a main shaft carrying pulleys, one fixed and the other loose, and a belt passing round all the pulleys, substantially as set forth. 115

8. The combination with the driving-roll, of a tube-holder, a support therefor, and a spindle extending from one end only of the holder and turning in said support, substantially as set forth. 120

9. The combination with the driving-roll, of a tube-holder, a support therefor, a spindle extending from one end only of the holder and turning in said support, and a pivoted 125

arm to which the support is jointed, substantially as set forth.

10. The combination with the driving-roll, of a tube-holder, a support therefor, a spindle extending from the holder and turning in said support, and a pivoted arm to which the support is jointed by a universal joint, substantially as set forth.

11. The combination of the roll, tube-holder, and spindle extending from one end only thereof, a pivoted arm, and a box supporting the holder-spindle and pivoted to said arm, substantially as set forth.

12. The combination with the driving-roll, of a tube-holder, a support therefor, a spindle extending from the holder and turning in said support, a pivoted arm to which the support is jointed by a universal joint, and a connecting-rod 111, jointed to the holder, the 20 pivoted arm and the rod 111 also jointed to a fixed support, substantially as set forth.

13. The combination with the driving-roll, of a tube-holder, a support therefor, a spindle extending from the holder and turning in 25 said support, a pivoted arm to which the support is jointed by a universal joint, and a connecting-rod 111 jointed to the support and to a point eccentric to the pivot of said arm, substantially as set forth.

30 14. The tension device provided with two bars, one movable to and from the other, and L-shaped fingers carried by said bars and arranged alternately, a spring tending to separate the bars, and adjustable means for limiting the outward movement of the movable bar, substantially as set forth.

15. The combination of a swinging cop-spindle, stop devices and a tension device provided with two bars, one movable to and from 40 the other, L-shaped fingers carried by said bars and arranged alternately, a spring tending to separate the bars, adjustable means for limiting the outward movement of the movable bar, and means for shifting the movable 45 bar to separate the bars when the stop devices act, substantially as set forth.

16. The combination of the drive-roll and the cop-support and means for maintaining the conical cop and the drive-roll in contact 50 along a line in the plane of their axes, as the yarn mass grows and cop swings upward, substantially as set forth.

17. The combination with the tension and stop devices of a winding-machine, a winding-55 drum, spindle-support, and a reciprocating thread-guide having a notch to receive the yarn, of a plate over which the yarn passes and movable to lift the yarn out of the notch, and means for lifting the plate and opening 60 the tension on the movement of the stop device to stop the winding, substantially as set forth.

18. The combination with the driving-roll and cop-tube holder of a winding-machine, of

a means for driving the roll, a guide, means 65 for reciprocating the same, a clutch for connecting the roll with and disconnecting it from the driving means, a stop device, connections for opening the clutch when the stop device acts, a tension device, and connections 70 for releasing the tension when the stop device acts, substantially as set forth.

19. The combination with the driving-roll and cop-tube holder of a winding-machine, of a means for driving the roll, a guide, means 75 for reciprocating the same, a clutch for connecting the roll with and disconnecting it from the driving means, and means for carrying the yarn out of the guide when the clutch opens, substantially as set forth. 80

20. The combination with the driving-roll and cop-tube holder of a winding-machine, of a means for driving the roll, a guide, means for reciprocating the same, a clutch for connecting the roll with and disconnecting it 85 from the driving means, clutch-operating devices, means for carrying the yarn out of the guide, and connections between the clutch-operating and yarn-carrying devices, substantially as set forth. 90

21. The combination in a winding-machine, of a driving-roll, tension device, cop-tube holder and movable support therefor, detent for supporting the holder in an elevated position, a guide, a movable plate over which 95 yarn passes to the guide, stop-motion, and connections for opening the tension and raising the plate when the machine is stopped, substantially as set forth.

22. The combination with the driving-roll, 100 of a hollow shaft, a rod sliding in said shaft and turning therewith, a clutch device, the parts of which are connected with the shaft and rod respectively, stop-motion, and connections whereby to shift the rod when the stop-motion 105 acts, substantially as set forth.

23. The combination with the driving-roll, hollow roll-shaft and clutch-section connected with said shaft, of a rod sliding in the shaft, a second clutch-section carried thereby, and 110 a stop-motion and means for moving the rod to open the clutch when the stop-motion acts, substantially as set forth.

24. The combination of the roll, hollow shaft, sliding rod 35, rod 40 carrying an arm 115 swinging past the end of the rod 35, a spring for turning the rod 40, clutch device between the rod 35 and shaft, a detent for maintaining the parts in position with the arm away from the rod 35, and drop-wire and connections for 120 releasing the detent therefrom, substantially as set forth.

25. The combination of the driving-roll, stopping and starting device, detent for holding the said device out of stopping position, 125 a dog connected with said detent, lugs carried with the roll and adapted to engage the dog, and a drop-wire arranged to shift the dog into

engagement with said lugs on the breaking of a yarn, substantially as set forth.

26. The combination with the driving-roll and conical cop-tube holder and spindle, of a support for the spindle and arms 9 and rod 111 connected with said support and eccentrically pivoted, substantially as set forth.

27. The combination of the driving-roll, cop-tube holder, pivoted arms and rod each having a universal jointed connection with the holder at one end and pivoted eccentrically with respect to each other, substantially as set forth.

28. The combination of the drive-drum and conical cop-support, and means for controlling the cop-support to maintain the cop and drum in contact along the length of the cop during the entire winding, substantially as set forth. 15

In testimony whereof I have signed my name to this specification in the presence of two subscribing witnesses. 20

GEO. W. FOSTER.
